CLAIM

The ornamental design for an aircraft light, as shown and described.

DESCRIPTION

FIG. 1 is an elevation view of the ornamental design for an aircraft light;

FIG. 2 is a front elevation view;

FIG. 3 is a top elevation view;

FIG. 4 is a bottom elevation view;

FIG. 5 is a left elevation view;

FIG. 6 is a right elevation view;

FIG. 7 is a diagonal top elevation view;

FIG. 8 is a diagonal bottom elevation view;

FIG. 9 is a diagonal bottom elevation view, viewed from the side opposite that shown in FIG. 8;

FIG. 10 is front elevation view in situ upon an aircraft;

FIG. 11 is a diagonal elevation view in situ upon an aircraft;

FIG. 12 is a top elevation view in situ upon an aircraft; and, FIG. 13 is side elevation view in situ upon an aircraft.

The portions of the aircraft shown in broken lines are for the purpose of showing the environment in which the design may be seen and from no part of the claimed design.
